UNITED STATES PATENT OFFICE

GEORGE W. TARKINGTON, OF SILVER PLUME, COLORADO

ELECTRIC SIGN AND METHOD OF ITS OPERATION

Application filed December 20, 1923. Serial No. 681,888.

My invention relates to a method of operating electric signs and its primary object is to provide in combination with a sign representing a slogan, sentence or other related group of words in electrically illuminated characters, a switching apparatus which automatically directs the current flow to said characters during intermittent periods in a cyclic operation so that out of certain words of the sign other words are constructed which in the order in which they appear, form an expression or phrase preferably relating to the subject of the sign.

With the above object in view, my invention consists first, in spelling a word of the sign from letters contained in one or more other words of the same, by consecutively illuminating the letters of the spelled word until the entire word is illuminated, and simultaneously darkening the corresponding letters of the other word or words; second, in illuminating parts of one or more words of the sign exclusive of other parts of the same, to form words of different meaning which together with other words of the sign express a thought relative to its subject; and third, in accomplishing these actions in cyclic succession so as to produce a sentence, phrase or expression different from but relating to the words which actually constitute the sign.

An embodiment of my invention has been illustrated in the accompanying drawings which represent a sign consisting of the words

35 THERE IS
HEALTH
IN
FOR THOSE
40 WHOLE WHEAT

in the different aspects it assumes by the successive actions in the cyclic operation of the 45 switching apparatus which controls the flow

of current to the characters of which the sign is composed.

It will be understood that the wording of the sign in the illustration is given merely as an example to better explain the distinctive features of the invention and the novel results attained in its operation, and that any subject other than "WHOLE WHEAT" may be taken as a basis upon which to construct a sign in accordance with my invention as outlined hereinabove.

Figure 1 of the drawings shows in electrical connection with the display board of the sign, a diagrammatic representation of the development of a motor-driven rotary make-and-break apparatus of the commutator type which in the operation of the sign causes the characters of which the words of the sign are composed to be illuminated and darkened in the required order.

The other figures of the drawing show the sign in the different consecutive phases of the cycle, the characters of the sign which are illuminated having been drawn in outline and those which are darkened in full lines.

It will not be necessary to illustrate or describe any of the mechanical parts of the sign such as the electric motor, the rotary switch, or the means for transmitting motion from the one to the other since all these devices are well known in the art and do not form part of the present invention except in a general sense.

In the diagram shown in Figure 1, the black spaces 5 of the commutator rings 6 represent insulation, and the white represent the conductive portion of the strips. The commutator is designated in its entirety by the reference character 8.

The conductors of electricity connecting 85 the rings 6 with the different characters of the sign have been shown at 12 and the sign itself has been designated by the numeral 13.

Figure 1 represents the sign as it appears in day time when the switching apparatus is 90

in a condition of rest and the lighting circuit in which the sign is connected is broken by any convenient means, not shown.

In the daytime all the words of the sign are plainly readable at a distance with the exception of the words "FOR THOSE" which are painted in the same color as the background of the sign and which therefore can not be discerned except from a near point of view. The sign thus reads ordinarily "THERE IS HEALTH IN WHOLE WHEAT" which is the broad idea it is intended to express.

It is a well known fact, however, that in order to impress the average person or the casual observer, it is necessary that some action takes place which attracts and arrests his attention and this I accomplish by the operation of the sign as will now be described.

Considering Figures 2 to 12 in their regular order, the first action obtained by rotation of the commutator-switch after its electric lighting circuit has been completed and its motor has been set in motion, is the darkening of all the letters of the sign except "WHOLE WHEAT" which thus being flashed by itself upon a dark background, strikingly announces the subject of the sign.

In the next action, the words "THERE IS" are first illuminated after which the word "HEALTH" is illuminated letter by letter, while the corresponding letters of the words "WHOLE WHEAT" are simultaneously extinguished. Thus when the first letter H of "HEALTH" is illuminated, the letter H of "WHOLE" is extinguished; when the next letter E is illuminated the last letter of the word "WHOLE" is darkened and so on until the entire word has been spelled.

By thus constructing the word "HEALTH" the attention of the observer is not only maintained until the entire word is completed but the idea is conveyed to the mind of the observer that health is derived from whole wheat, or in other words, that the use of whole wheat produces health.

In the third action illustrated in Figure 4, the remaining letters of the words "WHOLE WHEAT" are extinguished so that the sign reads "THERE IS HEALTH", which is immediately followed by the illumination of the word "IN" and the words "WHOLE WHEAT", as shown in Figures 5 and 6, so that the sign now reads "THERE IS HEALTH IN WHOLE WHEAT" which emphasizes the idea previously conveyed by spelling the word "HEALTH" from characters of the words "WHOLE WHEAT".

In the next following action, the entire sign is darkened as shown in Figure 7, to indicate an intermission between the two series of actions in the cyclic operation, which though distinct from each other, conjunc-

tively impress the idea involved in the sign upon the mind of the observer.

The first series of actions hereinbefore described, taught that there is health in whole wheat and the second series teaches how health may be obtained by the use of whole wheat.

Commencing with Figure 8, the first action of the second series illuminates the words "THERE IS" while the other parts of the sign remain dark; in the second action the word "HEALTH" is illuminated so that the sign will read "THERE IS HEALTH".

The following action illuminates the words "FOR THOSE" and in the next action, illustrated in Figure 11, the letters "W", "H" and "O" of "WHOLE" and the letters "E", "A" and "T" of "WHEAT" are illuminated exclusive of the other letters so that now the sign reads "THERE IS HEALTH FOR THOSE WHO EAT", and in the next and last action of the cycle, the sentence is completed by illuminating the other letters of the words "WHOLE" and "WHEAT", and darkening all the other words of the sign.

It will thus be observed that the second series of successive actions produces the sentence "THERE IS HEALTH FOR THOSE WHO EAT WHOLE WHEAT" and that the entire cycle of actions show first the subject of the sign "WHOLE WHEAT", then impresses upon the observer in a striking manner that "THERE IS HEALTH IN WHOLE WHEAT", and finally advises that "THERE IS HEALTH FOR THOSE WHO EAT WHOLE WHEAT".

Having thus described my invention, what I claim and desire to secure by Letters Patent is:

1. A display device comprising a plurality of words composed of letters capable of separate illumination, the words representing a significant phrase and certain of the words having corresponding letters, and means for the illumination of one of the words exclusively, followed by the extinction of certain letters of the illuminated word consecutively and the simultaneous illumination of corresponding letters in a non-illuminated word.

2. A display device having a word composed of letters capable of separate illumination, certain of the letters of the word spelling a different word exclusive of the other letters of the same, and means for illuminating the entire word and then extinguishing said other letters whereby only the letters spelling the different word remain illuminated.

3. A display device comprising a word and letters additional to the letters of the word and corresponding with letters of the word, the several letters being capable of separate illumination, and means to illuminate the entire word and then extinguishing certain letters of the word and simultaneously illuminating corresponding letters outside the word.

4. A display device comprising a plurality
of words composed of letters capable of sepa-
rate illumination, certain letters of one word
corresponding with letters in another word,
5 or words and spelling a different word, and
means to illuminate one of the words exclu-
sively and then extinguishing letters of the
illuminated word and simultaneously illumi-
nating corresponding letters in another word
10 or words.

In testimony whereof I have affixed my sig-
nature.

GEORGE W. TARKINGTON.
